MASK

Leslie James Fitzsimmons, East Orange, N. J.

Application September 2, 1947, Serial No. 771,607

4 Claims. (Cl. 128—139)

1

This invention relates to masks and has more particular reference to masks suitable for use by surgeons, physicians, dentists, beauty operators and the like, for their own protection as well as that of the patient or other person undergoing treatment.

Masks of this nature have been suggested in the past but have invariably been objectionable mainly because their manner of attachment to the face of the wearer rendered them either uncomfortable or highly inconvenient to apply.

The present invention has as its primary object the provision of a mask suitable for use by surgeons, dentists, beauty operators and the like, which is relatively simple in construction and convenient to use, and which in addition will assure comfort to the wearer.

Another object of this invention resides in the provision of a mask of the character described which may be securely and comfortably worn by surgeons, dentists, beauty operators and the like, much in the same manner as spectacles are worn.

Still another object of this invention resides in the provision of a mask embodying a shield of transparent material which is connected to a frame for the support of the shield over the face of the person wearing the mask in a novel manner, assuring space for the nose of the user so as to eliminate the necessity for molding the shield to the profile of the face.

With the above and other objects in view, which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawing illustrates one complete example of the physical embodiment of the invention constructed according to the best mode so far devised for the practical application of the principles thereof, and in which:

Figure 1 is a perspective view of the mask of this invention;

Figure 2 is a side elevational view of the mask as shown in Figure 1 and illustrating its manner of use;

Figure 3 is a plan view of the blank from which the shield is made;

Figure 4 is a view of the mask looking down on top of the same; and

Figure 5 is a cross sectional view taken through Figure 1 along the plane of the line 5—5.

Referring now more particularly to the accompanying drawing in which like numerals indicate like parts, the numeral 10 generally des-

2

ignates the mask of this invention. The mask comprises a frame generally designated 11, and a shield 12. The frame is preferably made of light-weight metal and includes a bow piece 13 of a length to span the brow of a person wearing the mask, and temple pieces 14 connected to the outer extremities of downwardly depending leg portions 15 at the opposite ends of the bow piece. The temple pieces are preferably attached to the legs of the bow piece with a conventional hinge structure indicated at 16.

As seen in Figure 5, the bow piece 13 is substantially channel-shaped in cross section, having opposite flanges 17 bent back upon themselves with the channel opening to the underside of the bow piece. These flanges receive between them the upper edge portion of the shield 12, and the latter is securely anchored to the bow by clinching the flanges together as at 18 or, if desired, by cementing the shield in place between the flanges.

The bow piece 13 is preferably bowed outwardly as indicated in Figures 2 and 4 so as to roughly correspond to the shape of the forehead or brow of a person wearing the mask, and because of its bow-shape, likewise holds the shield 12 in an outwardly bowed condition.

The shield 12 is of a size to cover substantially the entire face of the user and is preferably made of thin transparent material such as plastic, Celluloid or any similar material having a degree of resiliency or flexibility. The mask is cut from a blank indicated at 20 in Figure 3, and the upper portion of the blank is notched as at 21 to provide a central tongue 22 between the notches and opposite side strips 23. The notches 21 are spaced apart a distance corresponding to the spacing of the human eyes and provide eye openings 24 when the blank is secured in place on the bow piece 13.

The strips 23 are shaped to fit the curve of the bow piece adjacent to the downwardly depending leg portions 15 thereof so that portions along the sides of the strips are received between the flanges of the legs 15 while the upper extremities of the strips are received between the flanges adjacent to the junctions between the bow piece and its downwardly depending leg portions.

The central tongue 22 of the blank is longer than the strips 23 and its outer end is secured between the flanges of the bow piece at the mid-portion thereof so that the excess length of the tongue causes the same to buckle intermediate its length as shown in Figure 2. When secured in position, therefore, the outer portion of the tongue is held by the bow piece in a more or less downwardly depending condition while the inner portion of the tongue adjacent to its connection with the body of the blank is caused to lie nearly horizontally as at 25; the deformation of the

tongue thereby reacting on the central portion of the body of the shield to bow the same outwardly and thereby provide clearance for the nose of the person wearing the mask.

It is important to note that the medial portion 5 26 of the tongue 22 in the deformed position of the tongue provides a ledge or rest which is engageable with the nose of a person wearing the mask adjacent to the bridge of the nose and which ledge cooperates with the temple pieces 14 to 10 comfortably support the mask on the face of the wearer.

It is also important to note that the opposite side edges of the tongue 22 are tapered so as to converge toward the inner extremity of the tongue to define a narrow portion 28 intermediate the length of the tongue. This narrow portion renders the tongue easily bendable to define the ledge 26 and it will be apparent that the location of the ledge may be accurately predetermined at 15 the time the shield is blanked out merely by shifting the narrow portion 28 either toward the inner or outer extremity of the tongue.

As clearly shown in Figure 2, the ledge 26 on the tongue serves to hold the bow piece 13 at an elevation adjacent to or slightly above the line of the brows and inasmuch as the bow piece is bowed outwardly to clear the brow, it will be apparent that the mask of this invention may be worn by persons having normal eyesight as well 20 as those requiring spectacles, as the ordinary spectacles will not interfere with proper use of the mask.

The provision of the ledge or bridge 26 along with the temple pieces 14 enables the mask of this invention to be worn in the same manner as spectacles and provides the same degree of comfort and security to the wearer. This results in a substantial improvement over past 35 masks of this nature wherein ties or straps were employed to retain the mask in place.

From the foregoing description taken in connection with the accompanying drawing, it will be apparent that this invention provides a highly improved mask for use by surgeons, 40 dentists, beauty operators and the like.

What I claim as my invention is:

1. A mask of the character described comprising: a frame including a bow piece of a length to span the brow of a person wearing the mask and bowed outwardly to substantially correspond to the shape of the brow, downwardly depending leg portions on the opposite extremities of the bow piece, and temple pieces connected to said downwardly depending leg portions of said bow piece to aid in supporting the mask on the head of the wearer; a shield having its upper edge portions secured to said bow piece and suspended therefrom to cover the nose and mouth of a person wearing the mask; and offset means integral with said shield and centrally thereof beneath the bow piece defining a ledge adapted to engage the bridge of the nose of the wearer to hold the body of the shield spaced from the end of the wearer's nose and adapted to cooperate with said temple pieces to support the mask on the head of the wearer.

2. A mask of the character described comprising: a frame including a bow piece of a length to span the brow of a person wearing the mask, and temple pieces connected to the opposite end portions of said bow piece adapted to be engaged over the ears of a person wearing

the mask to aid in supporting the mask in position on the head of the wearer; a relatively transparent shield of a size to substantially cover the face of the wearer; connections between opposite side portions of the shield and said bow piece adjacent to the temple pieces thereon by which the shield is suspended from said bow piece; another connection between said bow piece and a central portion of the shield therebeneath by which said central portion of the shield reacts against the body of the shield to hold the same bowed outwardly to clear the nose of a person wearing the mask; and a ledge on said central portion of the shield adjacent to its connection with the bow piece engageable with the nose of a person wearing the mask to cooperate with the temple pieces in supporting the mask in place.

3. The mask set forth in claim 2 further characterized by the provision of apertures in the shield beneath the bow piece and at opposite sides of said ledge affording unobstructed vision for persons wearing the mask.

4. A mask of the character described comprising: a frame including a bow piece of a length to span the brow of a person wearing the mask; and temple pieces connected to the opposite end portions of the bow piece and adapted to pass over the ears of a person wearing the mask to aid in supporting the same in position on the head of the wearer; a shield of relatively light transparent material having a degree of flexibility and of a size to substantially cover the face of a person wearing the mask; said shield having its upper edge portion notched to provide spaced eye openings and to form a tongue between said notches; connections between the opposite side portions of the shield bounding said notches and said bow piece by which the shield is suspended from the bow piece; a connection between the outer end portion of said tongue and the bow piece by which the tongue is held in a flexed condition with its outer portion substantially upright and its inner portion projecting at an outward angle thereto and reacting upon the central portion of the body of the mask with which it connects to hold the same bowed outwardly sufficient to clear the end of the nose of a person wearing the mask; and a ledge on said tongue at the junction between said upright and outwardly projecting portions thereof to act as a nose rest engageable with the nose of a person wearing the mask to thus cooperate with the temple pieces in supporting the mask on the face of the user.

LESLIE JAMES FITZSIMMONS.
